UNITED STATES PATENT OFFICE.

WILLIAM GERMINER, OF PUEBLO, COLORADO, ASSIGNOR OF TWO-FIFTHS TO MARSHALL L. BRITTAINE, OF PUEBLO, COLORADO.

TRAIN-CONTROLLING APPARATUS.

No. 870,427.

Specification of Letters Patent.

Patented Nov. 5, 1907.

Application filed April 2, 1907. Serial No. 366,984.

To all whom it may concern:

Be it known that I, WILLIAM GERMINER, a citizen of the United States, residing at Pueblo, in the county of Pueblo and State of Colorado, have invented new and useful Improvements in Train-Controlling Apparatus, of which the following is a specification.

The invention relates to an improvement in train controlling apparatus, whereby the travel of one or more trains is automatically controlled when they are 10 within prescribed distances of each other.

The main object of the present invention is the provision of an automatic train controlling apparatus including a series of normally open circuits which are closed through the presence of two trains within prescribed limits, the construction including a means 15 adapted for actuation upon the closing of the circuits to automatically set the brakes on the respective trains to prevent further travel of the same.

The invention will be described in the following 20 specification, reference being had particularly to the accompanying drawings, in which:

Figure 1 is a perspective view illustrating the application of my improved apparatus, Fig. 2 is a diagrammatic view illustrating particularly the track circuits 25 for the controlling of trains, two opposing engines being shown on adjacent track sections, Fig. 3 is a similar view showing two engines in different positions with respect to the central station, Fig. 4 is a similar view showing the engines on remote sections.

Referring particularly to the drawings, wherein is 30 illustrated the preferred form of the apparatus, it will be noted that one track rail, as 1, is bonded throughout, making a continuous electrical conductor. The opposing rail 2 is similarly bonded but also divided by 35 insulation 3 into a series of sections 4, 5, and 6, it being understood that there may be any number of these sections and that they may be of any desired length. The section 1, which may be termed the station section, is preferably adjacent an ordinary stopping point for the 40 trains, or in the immediate neighborhood of an operator from whom the engineers may receive orders.

At a convenient point adjacent the section 1 I arrange 45 a source of energy 7, the line conductors 9 and 10 of which are connected by conductors 11 and 12 with the sections 4 and 5 respectively. The conductor 9 is also in electrical communication with the section beyond section 4, as 6, through a conductor 13, while the section beyond section 5 in a direction opposite to section 6 is in electrical connection with the conductor 10 50 through a conductor 14. The sections in opposite directions beyond the station section 4 are thus each in direct electrical communication with the service conductors from the source of energy. Each section is thus in electrical communication with every other sec-

tion through a normally open circuit, as will be clearly 5 apparent from Figs. 2, 3, and 4.

The apparatus carried by the locomotive forms a material part of the present invention, which on reference to Fig. 1 is seen to comprise a transverse bar 15 suitably connected to the locomotive structure and carrying adjacent its ends spring arms 16 which terminally support rollers 17 and 18, so arranged as to bear upon the respective track rails at all times, the tension of the arms 16 maintaining sufficient contact between the rollers and rail to insure a good electrical connection. Mounted in the engine cab is an electro-magnet 19, 60 preferably of the double type, which is in electrical communication with the respective rollers 17 and 18 through the medium of conductors 20 and 21.

The electro-magnet 19 is supported adjacent the service pipe 22 for the air brake system, which pipe is provided with the usual engineer's valve 23 for manual control of the brakes by the engineer. The pipe 22 is 65 preferably provided with a cylinder extension 24 open at the ends and breaking the continuity of the pipe 22, 70 said cylinder being arranged across the length of the pipe and the respective terminals of the pipe section adjacent the cylinder being secured thereto to provide communication between said sections only through the cylinder. Mounted within the cylinder 24 is a valve 75 body 25, centrally reduced at 26 to provide an annular passage 27 to permit the passage of air around the reduced portion 26 of the valve and through the respective sections of the pipe 22 when said valve is disposed to align the reduced portion with the pipe sections.

The valve body is suitably packed at the ends to prevent escape of the air from the cylinder when the valve is in normal or cylinder closing position, and is further provided with a bar 28 extending toward the electro-magnet 19 and having a hook terminal 29. The electro-magnet 19 is provided with an armature 30 carried upon one end of the lever 31, which lever is fulcrumed at 32 upon a suitable fixture in advance of the electro-magnet and is provided at its forward or free terminal with a hook 33 adapted to co-operate with the hook 29 of 80 the valve body. The spring 34 is connected to a fixed part of the frame structure and to the lever 31 in advance of the pivot, said spring serving to normally maintain engagement of the hooks 29 and 33 when the electro-magnet is de-energized, but ineffective to maintain the lever in such position against the pull exerted by the energized magnet. The relatively forward end of the valve body is connected through the medium of a coil spring 35 to a hand lever 36, adapted to be locked in 85 any desired position to the usual notched segment, not shown.

A by-pass or escape pipe 37 is connected to the train pipe 22, on the train side of the cylinder 24, and is in 90 95 100 105

A by-pass or escape pipe 37 is connected to the train pipe 22, on the train side of the cylinder 24, and is in

open communication with the cylinder immediately adjacent the relatively rear end of the latter.

One of the conductors 20 or 21 is provided with a manually operable switch 38 arranged within convenient reach of the engineer so that he may break the electro-magnet circuit at will.

As the respective track circuit terminals are arranged in different blocks or sections, it is obvious that it is impossible for any one train during its travel lengthwise of 10 the track to complete a circuit and thereby energize the electro-magnet 19. If, however, two trains, either approaching each other or traveling in the same direction, are within the prescribed limits of the station sections a complete circuit is formed through the track circuit, 15 whose terminals include the respective occupied sections, the wheels 17 of each locomotive apparatus, the conductors 20 of each electro-magnet circuit, the electro-magnets 19 of each locomotive, the conductors 21 of each electro-magnet circuit and the rollers 18 of each 20 locomotive apparatus to the continuous rail conductor 1. The energization of each of the electro-magnets attracts the armature of each electro-magnet and operates the lever to disengage its hook from the hook 29 of the valve body. The spring 35 thereupon operates to move 25 the valve body in the forward direction, shifting the port 27 out of alignment with the pipe sections of pipe 22, and moving the relatively rear end of said body beyond the outlet end of the by-pass 37. This operates to effectually complete the train pipe and set the brakes 30 in the usual manner, thereby bringing the train to a stop. The engineer may then break the circuit, through the medium of the switch 38, and proceed with his train under perfect control to the station section 4 for orders, or until the interfering train is in sight. The 35 apparatus is reset after deenergization of the electro-magnets by releasing the lever 36 and moving the valve body into normal position with its hook 29 engaging the hook 33 of the lever.

The lever 36 is a material part of the present invention, as I contemplate thereby so tensioning the spring 35 as to insure a comparatively slow movement of the valve body when released from the armature lever. This operation in conjunction with the comparatively 40 reduced bore of the escape 37 insures a gradual reduction of train pipe pressure and a consequent steady and gradual application of the brakes.

The system described will thus effectually prevent collisions as the brakes of the interfering trains will be automatically applied when said trains are within pre- 50 scribed limits of the central or station section.

While preferring the details of structure illustrated and described it is to be understood that various changes and modifications thereof may be resorted to without affecting the function of the apparatus, and it 55 is, therefore, to be understood that such changes and

variations as may fall within the scope of the appended claims are to be considered as within the spirit of the present invention.

Having thus described the invention what is claimed as new, is:—

1. A train controlling apparatus including a series of independent track circuits, normally open circuits carried by the locomotives and adapted to be closed in conjunction with each other and with any one of the track circuits, an electro-magnet in each of the locomotive circuits, and a bleed valve for the train pipe operated on the movement of said armature. 65

2. A train controlling apparatus including a series of independent track circuits, normally open circuits carried by the locomotive and adapted to be closed in conjunction with each other and with any one of the track circuits, an electro-magnet included in each locomotive circuit, a bleed valve arranged in the train pipe, means connected with the armature of the electro-magnet to lock said valve in closed position, and means to move the valve to open position upon the operation of the armature in the energization of the electro-magnet. 70 75

3. A train controlling apparatus including a series of independent track circuits, normally open circuits carried by the locomotive and adapted to be closed in conjunction with each other and with any one of the track circuits, an electro-magnet included in each locomotive circuit, a bleed valve arranged in the train pipe, a by-pass leading from said pipe and normally closed by a valve, means for maintaining said valve in closed position during deenergization of the electro-magnet, and means for moving the valve to open position upon the energization of the magnet. 80 85

4. A train controlling apparatus including a series of independent track circuits, normally open circuits carried by the locomotive and adapted to be closed in conjunction with each other and with any one of the track circuits, an electro-magnet included in each locomotive circuit, a bleed valve arranged in the train pipe, a by-pass leading from said pipe and normally closed by a valve, means for maintaining said valve in closed position during deenergization of the electro-magnet, a spring for moving the valve to open position, a hook projecting from the valve, and a hook lever projecting from the armature and adapted to engage the valve hook when the electro-magnet is deenergized. 90 95 100

5. A train controlling apparatus including a series of independent track circuits, normally open circuits carried by the locomotive and adapted to be closed in conjunction with each other and with any one of the track circuits, an electro-magnet included in each locomotive circuit, a bleed valve arranged in the train pipe, a by-pass leading from said pipe and normally closed by a valve, means for maintaining said valve in closed position during deenergization of the electro-magnet, a spring for moving the valve to open position, a hook projecting from the valve, a hook lever projecting from the armature and adapted to engage the valve hook when the electro-magnet is deenergized, and means for adjusting the valve operating spring. 110 115

In testimony whereof, I affix my signature in presence of two witnesses.

WILLIAM GERMINER.
